UNITED STATES PATENT OFFICE.

WALTER S. ROCKWELL, OF NEW YORK, N. Y.

FURNACE PREHEATER AND SHIELD.

1,101,961.

Specification of Letters Patent. Patented June 30, 1914.

Application filed February 10, 1914. Serial No. 817,749.

To all whom it may concern:

Be it known that I, WALTER S. ROCKWELL, a citizen of the United States, residing at 300 West One Hundred and Sixth street, New York, county of New York and State of New York, have invented certain new and useful Improvements in Furnace Pre-heaters and Shields, fully described and represented in the following specification and the accompanying drawings, forming a part of the same.

This invention relates to a means for utilizing the waste heat, which escapes from the working-opening of heated furnace-chambers, to pre-heat the air which is used in the combustion of the fuel in such furnaces, and it also relates to such a construction of the device as to provide a shield for protecting the operator.

20 The invention consists partly of a pre-heater containing an air-conduit supported outside the casing of the furnace above the working-opening, with a suitable space between the same and the furnace-front to admit the heated gases which escape from the working-opening, and which are driven upwardly by a blast-pipe located just beneath the working-opening.

25 The term pre-heater is used herein to embrace the associated parts which conduct the air through an air-conduit to be heated and which expose such conduit to the heat of the waste-gases. The conduit-pipes are connected at their opposite ends respectively with an air blower and with the combustion-chamber of the furnace, and may be so disposed as to form, themselves, a shield to protect the workmen from the heat of the gases, or the pipes may be combined with a 30 plate of metal or earthen material, or other substance adapted to intercept the heat from such gases.

35 The heated gases which escape from the working-opening have a natural tendency to rise and thus contact with the pipe or pipes which form the air-conduit, and therefore greatly heat the air in such pipes before it is used for combustion. To prevent the movement of the gases toward the operator, 40 a blast-pipe may be located outside of the furnace-front just below the lower edge of the working-opening, and perforated or slotted to blow the heated gases upwardly into contact with the air-conduit, from which 45 they escape at a point too high to directly affect the operator.

The air-conduit may be made of a hollow casting or castings, or of one or more pipes connected together and supported adjacent to the furnace-front. The air-conduit or 50 pre-heater may itself operate as a shield to protect the operator from the radiation of heat, or the shield may consist of a plate of metal or baked clay operating to confine the waste-gases in proximity to the pre-heater, or it may be part of a casing forming an inclosed chamber about the pre-heater. A blast-pipe directing a blast upwardly from the lower edge of the working-opening can be used where the articles to 55 be heated are placed wholly within the furnace, as indicated by the bars and blocks in the drawing.

Various modifications may be employed which will be understood by reference to 60 the annexed drawing, in which—

Figure 1 is a front elevation of a furnace with pre-heater and shield, the right-hand half of the shield being broken away and represented merely by dotted lines, in 65 order to expose the air-conduit. Fig. 2 is a cross-section on line 2—2 in Fig. 1, and Fig. 3 is a plan of the furnace-front, shield and air-conduit. Fig. 4 shows a pre-heater made of air-pipes arranged to serve as a 70 shield; Fig. 5 shows the air-conduit having pipes arranged in sloping series; Fig. 6 is a plan of the parts shown in Fig. 5.

In Figs. 1 to 3 the heating-chamber 1 is shown with a working-opening 2 extended 75 through the furnace-front 3, the term "extended" meaning an extension from the heating-chamber outward through such furnace-front. A shield 4 is supported outside of the furnace-front just above the 80 working-opening by brackets 43, thus permitting access to the working-opening while intercepting the heated gases most effectively, and air-conduit-pipes 5 are connected in a series by return-bends 7 and a series 85 supported upon the furnace-front 3 by bracket 6 which are shown in front-view in Fig. 1, and in side-view in Fig. 2, and in plan in Fig. 3. The heads are appropriately connected with an air-supply-pipe 8 and with the burners 10. A cock 8' regulates the supply of air to the pre-heater, and cocks 11' connected to fuel-supply-pipes 11 regulate the supply of fuel to the burners, located just below the level of the working-opening 90 and perforated to discharge an air-blast upwardly into the space between the air-con- 95

duit and furnace-front. Such air-blast intercepts the heated gases and drives them upwardly into such space, the heat of such waste-gas being absorbed in great part by the conduit and the air contained therein, is utilized in the combustion of the fuel. The blast-pipe 12 is connected to the same air-supply-pipe 8 as the air conduit 5. A sill may be projected from the lower edge of the working-opening toward the blast-pipe 12, but such sill is not material to the operation of the device.

In Fig. 3, the shield 4 is shown faced with an inner layer 4^a of non-heat-conducting material like asbestos, and an outer layer 15 may also be used, so as to protect the operator from the heat of the rising gases, but the shield may be made wholly of non-heat-conducting material if desired. The term 20 "non-conductor of heat" is employed herein to express the character of any agent adapted to reduce radiation from the heated gases toward the operator, and does not imply an entire intercepting of the heat.

25 In the construction shown in Figs. 4 to 6, the ends of the conduit pipes 5' are shown connected with headers 7 which contact with the furnace-front and with the shield, and the headers may thus support a shield 30 upon the furnace-front while they inclose the space in which the conduit pipes are located, and thus confine the heated gases more closely thereto. In Figs. 4 to 6, the pipes 5' are placed in a sloping series so as 35 to intercept more effectively the heated gases which rise between the pipes and the furnace-front. In Fig. 4, an inclined series of horizontal pipes is shown disposed close to one another so that they operate both as 40 a pre-heater and a shield, a sloping space being provided between such pipes and the furnace-front for the upward passage of all the heated gases.

45 In all the constructions described, the blast-pipe may be employed to operate from the bottom of the working-opening, to drive the heated gases upwardly into the space provided behind the shield or pre-heater pipes.

50 In furnaces for annealing and tempering, a much lower pressure is maintained than in furnaces for forging, and in such annealing furnaces the gases escape from the working-opening with so little force that 55 they may rise into the space between the pre-heater and the furnace-front without any extraneous means of guiding or directing them, and the utility is thus obvious of an air-conduit combined with or forming a shield, and I have therefore made claim to the same irrespective of any direct means as an air-blast for driving the heated gases upwardly into contact with the air conduit.

55 It is immaterial how the shield be supported with suitable space behind it for

the upward passage of the heated gases, or how the conduit-pipes are sustained in such space, as the essential feature of the arrangement is their relation to the furnace-front and the working opening.

Having thus set forth the nature of the invention what is claimed herein is:

1. In a heating-furnace, the combination, with a heating-chamber having a working-opening extended through the front from which waste-gases may escape, of an air-conduit supported in the path of the rising gases in proximity to the furnace-front and working-opening, with its ends connected respectively to an air-supply pipe and to 80 the combustion-chamber of the furnace, and an air-blast directed upwardly upon the waste-gases escaping from the working-opening, and operating to drive the gases against the air-conduit to heat the air passing therethrough.

2. In a heating-furnace, the combination, with a heating-chamber having a working-opening extended through the front from which the waste-gases may escape, of a pre-heater having an air-conduit formed of a series of pipes mounted close together to operate as a shield and connected for the passage of air therethrough, and supported before the front with space for the passage 95 of heated-gases, and an air-blast directed upwardly upon the waste-gases escaping from the working-opening and operating to drive the gases upwardly into said space to heat the air-conduit.

3. In a heating-furnace, the combination, with a heating-chamber having a working-opening extended through the front from which waste-gases may escape, of a pre-heater having an air-conduit formed of a 100 series of pipes mounted close together to operate as a shield and connected for the passage of air therethrough, and supported in an inclined position before the furnace-front with space between such pipes and the front for the upward passage of heated-gases, and an air-blast directed upwardly upon the waste-gases escaping from the working-opening and operating to drive the 105 gases upwardly into said space to heat the air-conduit.

4. In a heating-furnace, the combination, with a heating-chamber having a working-opening extended through the front from which waste-gases may escape, of a pre-heater having an air-conduit formed of a 110 series of horizontal pipes mounted close together to operate as a shield and connected together for the passage of air therethrough, and supported in an inclined position before the furnace-front with space between the pipes and the front for the upward passage of heated-gases, an air-blast-pipe arranged below the working-opening and operating to drive the waste-gases upwardly 115

upon such conduit-pipes, and the ends of the pipes being connected respectively with an air-supply and with the combustion-chamber of the furnace.

5 5. In a heating-furnace, the combination, with a heating-chamber having a working-opening extended through the front from which waste-gases may escape, of an air-conduit supported before the furnace-front 10 in the path of the gases rising from the working-opening, and an air-blast-pipe arranged below the working-opening and adjacent thereto and operating to drive the waste-gases upwardly against the air-conduit to heat the air passing therethrough.

6. In a heating-furnace, the combination, with a heating-chamber having a working-opening extended through the front from

which waste-gases may escape, of an air-conduit supported before the furnace-front 20 in the path of the gases rising from the working-opening, and having its ends connected respectively to the combustion-chamber of the furnace and to an air-supply-pipe, and a branch of such air-supply-pipe ex- 25 tended in a blast-pipe near the lower edge of the working-opening and directing a blast upwardly against the air-conduit to heat the air passing therethrough.

In testimony whereof I have hereunto set 20 my hand in the presence of two subscribing witnesses.

WALTER S. ROCKWELL.

Witnesses:

EDWARD S. LONG,
JOSEPH A. DOYLE.

It is hereby certified that in Letters Patent No. 1,101,961, granted June 30, 1914, upon the application of Walter S. Rockwell, of New York, N. Y., for an improvement in "Furnace Preheaters and Shields," an error appears in the printed specification requiring correction as follows: Page 1, line 109, after the word "burners" strike out the comma and insert a period (.) and the words *A blast-pipe is;* and that the proper corrections have been made in the files and records of this office and are hereby made in the said Letters Patent.

Signed and sealed this 11th day of August, A. D., 1914.
